UNITED STATES PATENT OFFICE.

PETTER C. N. PEDERSON, OF WEST SUPERIOR, WISCONSIN.

FLUID-PRESSURE MOTOR.

SPECIFICATION forming part of Letters Patent No. 596,614, dated January 4, 1898.

Application filed February 17, 1897. Serial No. 623,854. (No model.)

To all whom it may concern:

Be it known that I, PETTER C. N. PEDERSON, a citizen of the United States, residing at West Superior, in the county of Douglas 5 and State of Wisconsin, have invented a new and useful Fluid-Pressure Motor, of which the following is a specification.

My invention relates to fluid-pressure motors adapted to utilize the expansive force of steam, compressed air, gas, or any equivalent thereof; and the object in view is to provide novel and efficient means for actuating a piston continuously in a uniform direction, the cylinder or expansion-chamber in which the piston receives its impulse from the motive agent being straight, and, furthermore, to provide such a relative construction of piston and expansion-chamber that the power of the motor may be multiplied to any desired extent by multiplying the number of expansion-chambers and arranging the same in series to cause successive operation of the motive agent upon the same piston or to cause simultaneous operation of the motive agent upon different piston-heads connected by a common carrier or piston-rod.

Further objects and advantages of this invention will appear in the following description, and the novel features thereof will be particularly pointed out in the appended claims.

In the drawings, Figure 1 is a vertical longitudinal section of a motor constructed in accordance with my invention, one of the expansion-chambers and contiguous parts being shown in section and another in elevation. Fig. 2 is a detail view in perspective of the inlet end of one of the expansion-chambers, including the gate-locks and valve mechanism. Fig. 3 is an end view of the same, partly broken away to show the trips of the advance gate-locks. Fig. 4 is a horizontal sectional view of the same. Fig. 5 is a detail view in perspective of one of the advance-gate-lock trips detached. Fig. 6 is a similar view of one of the reverse gate-locks detached. Fig. 7 is a detail view of the packing-strip and cooperating blocks used in connection with the wings of the gates. Fig. 8 is a plan view of one of the pistons. Fig. 9 is a transverse vertical section of the same. Fig. 10 is a detail view in perspective of an arm of one of

the carrier guides or wheels. Fig. 11 is a similar view of contiguous connected links of one of the carrier members.

55

Similar numerals of reference indicate corresponding parts in all the figures of the drawings.

The mechanism embodying my invention includes a straight cylinder or expansion-chamber 1, at the inlet end of which are arranged duplicate opposite coöperating gates 2, each having a plurality of wings 3, said gates being adapted to rotate in opposite directions, as indicated by the arrows in Fig. 1 at a, to successively bring the contiguous wings in vertical or transverse alignment, with their contiguous edges approximately in contact, and thereby form a fixed abutment, between which and the moving abutment 70 formed by the piston-head 4 is admitted the motive agent by means of an inlet-valve 5, controlling an inlet-port 6, preferably arranged in the side of the chamber contiguous to the plane of the fixed abutment. Motive 75 agent is admitted to the valve-chamber 7 by means of a supply-pipe or conductor 8.

A plurality of piston-heads are supported by a common carrier 9, which is of endless and flexible construction and traverses suitable spaced guides 10, which in the construction illustrated consist of wheels. The arms 11 of these wheels are provided with inwardly-extending webs 12, having terminal seats 13, which are constructed cross-sectionally to 85 correspond with the half-section of the carrier member, the carrier comprising any desired number of carrier members, which in the construction illustrated consist of jointed rods. The carrier members are shown in the drawings as being of round construction, and each member is sectional to form a plurality of links connected in series with interlocking joints or hinges, as shown at 14.

The piston, which comprises the piston-heads 4 and the carrier to which they are attached, moves in the direction indicated by the arrow b in Fig. 1, and as the piston-heads successively enter the expansion-chamber through the end fitted with the oppositely-rotatable gates 2 the latter turn through an arc equal to the number of degrees of a circle comprehended between the extremities of the wings, and therefore with gates provided

with four wings, as in the construction illustrated, the gates will move at each operation through an arc equal to ninety degrees, and as subsequent to each movement of the gates 5 the motive agent is admitted to the expansion-chamber between the fixed abutment formed by the coacting or alined wings of the gates and the piston-head which has just entered the expansion-chamber it is necessary to employ means for preventing the backward rotation or reverse movement of the gates. The means employed for this purpose consist of reverse gate-locks 15, mounted in suitable guides in opposite side walls of the expansion-chamber and projecting at their inner edges 10 in rear of the alined or operative wings of the gates, said locks having the rear sides of their projecting edges beveled, as shown at 16, to receive the pressure of the extremities of the piston-head which is about to enter the expansion-chamber, whereby said locks may be repressed out of the path of such piston-head, the length of the piston-head being equal to 15 the width of the expansion-chamber. These reverse gate-locks are yieldingly held in their normal or operative positions with relation to the operative wings of the gate by means of springs 17. (Shown clearly in Fig. 2.) It is also desirable to prevent excessive forward or 20 advance rotation of the gates, whereby they may be positively stopped when they reach a position in which the contiguous wings are in alinement, and hence are adapted to form the fixed abutment for the succeeding 25 operation of the motive agent, and the means which I have devised for accomplishing this purpose consist of advance gate-locks 18, arranged in the paths, respectively, of those wings which, after having served as fixed 30 abutments, have been moved by the entrance of a piston-head into an inoperative position out of the path of the said entering piston-head to complete the top and bottom walls, respectively, of the expansion-chamber, (also 35 shown in Fig. 1,) the contiguous edges of said top and bottom walls, which have been cut away to allow the said movement of the wings of the gates, being provided with projections 40 19 to fit in and snugly close the notches 20, formed in the meeting edges of the wings to allow the passage of the carrier members. These advance gate-locks are also yieldingly held in their operative positions, as by means 45 of springs 21, and in the construction illustrated the pair of advance gate-locks which I preferably use at each side of the expansion-chamber are connected for simultaneous operation by a frame comprising a slide 22, having arms 23, said arms projecting from the 50 extremities of the slide and being terminally attached to the locks. Any suitable means may be employed for guiding the slide—such as spurs 24, fitting in suitable seats in the side walls of the expansion-chamber. In connection with this construction I also employ 55 a trip 25, mounted in a guide in the side wall of the expansion-chamber and connected to

the slide or yoke, the actuating-spring 21 being arranged to bear directly against the trip, and the latter, which projects at its inner edge 70 beyond the inner surface of the side wall of the expansion-chamber, being beveled, as shown at 26, for contact with the contiguous extremity of the piston-head. Hence as the piston-head enters the front or receiving end 75 of the expansion-chamber it first actuates the trips 25 and thereby disengages the advance gate-locks from the gate-wings, and while holding the advance gate-locks in their retracted position the piston also trips the return gate-locks and bears against the alined or operative wings of the gates. The continued advance movement of the piston-head 80 then causes the gates to swing upon their parallel axes and brings the succeeding wings 85 into operative position in rear thereof preparatory for the admission of motive agent to give an impulse to the recently-entered piston-head. The trips 25 are limited as to inward movement under the impulse of the 90 actuating-springs 21 by means of terminal stop-ears 25^a. (See Figs. 3 and 5.)

As above described, the meeting edges of the gate-wings are cut away or notched to receive the piston-carrier members, and in order to prevent leakage of the motive agent around the piston-carrier members and also in the joints between the alined piston-wings the latter are provided with edge packing-strips 27, yieldingly held in operative position by actuating-springs 28 and limited in extension by stop-pins 29, engaging suitable slots in the strips, said strips having notches 30 for the reception of the carrier members. The strips are also provided with independently-movable members or blocks 31, provided with concaved faces 32, said independently-movable members or blocks being let into cavities 33 in the strips and being yieldingly held in their operative position in close 105 contact with the carrier members by means of independent actuating-springs 34. These independent members or blocks 31 are also limited as to extension by pins 35, engaging suitable slots. End packing-strips 36 are 110 also employed in connection with the gate-wings, the contiguous extremities of the edge packing-strips 27 and end packing-strips 36 being halved and overlapped, as shown. Furthermore, the piston-heads are provided with 115 packing-strips 37, actuated by springs 38, and in order to break the shock of the contact of the piston-heads with the operative wings of the gates I employ cushion-springs 39, preferably reinforced by an inclosed auxiliary 120 spring 40.

Any suitable construction of valve mechanism may be employed in connection with the devices above described; but that which I have found to be efficient consists of a rocker 130 41, of bell-crank-lever construction, of which one arm is connected by a link 42 with the valve-stem 43, while the other arm is provided with a pin 44, operating in a cam-groove 45.

The cam when used in connection with one of the guides 10 is preferably made as a groove, (see Fig. 1;) but it is obvious that a cam driven by or operating in connection with the pistons 5 may be substituted therefor without departing from the spirit of this invention.

From the above description it will be seen that the piston, which comprises the series of spaced piston-heads and a connecting-carrier, 10 may be used in connection with one or more expansion-chambers to receive a continuous motion in a uniform direction, the construction illustrated in the drawings embodying two expansion-chambers arranged at opposite 15 sides of the carrier and receiving the piston-heads successively; but it is obvious that in order to increase the power the number of expansion-chambers coöperating with the piston may be multiplied; and, furthermore, it 20 will be seen that the utility of the mechanism as described is not limited to any particular motive agent, either steam, compressed air, gas exploded at the proper intervals by means not shown but well known in the art, or any 25 equivalent of these expansive agents being applicable to the mechanism as set forth.

Inasmuch as the exhaust from each expansion-chamber occurs at the outlet end thereof and follows the piston-head, it will be seen 30 that the expansive force of the motive agent is exerted upon the piston-head throughout the travel of the latter, and in order to control the exhaust the number of expansion-chambers desired for a particular motor may 35 be arranged, as shown in the drawings, within a common casing 46, provided with an exhaust-port 47, said casing being supported by suitable standards 48 or their equivalents.

Various changes in the form, proportion, 40 and the minor details of construction may be resorted to without departing from the spirit or sacrificing any of the advantages of this invention.

Having described my invention, what I 45 claim is—

1. A fluid-pressure motor having an expansion-chamber, a piston comprising a plurality of flexibly-connected piston-heads adapted to pass successively through the expansion-50 chamber in a common direction, coöperating movable gates located at the inlet end of the expansion-chamber and adapted to be actuated by the successive engagement of the piston-heads therewith, to open the inlet end 55 of the expansion-chamber for the passage of the piston-heads, and gate-locks for normally holding the gates in their closed or adjusted positions, and having trips for engagement by the piston-heads, whereby the gates are 60 released preparatory to contact therewith of a piston-head, substantially as specified.

2. A fluid-pressure motor having an expansion-chamber, a piston comprising a plurality of flexibly-connected piston-heads adapted 65 to pass successively through the expansion-chamber in a common direction, coöperating opposite swinging gates located at the inlet

end of the expansion-chamber and adapted to be actuated by the successive engagement of the piston-heads therewith, to open the inlet end of the expansion-chamber for the passage of the piston-heads, and gate-locks for normally holding the gates in their closed or adjusted positions, and having trips for engagement by the piston-heads, whereby the 70 gates are released preparatory to contact therewith of a piston-head, substantially as specified.

3. A fluid-pressure motor having an expansion-chamber, a piston comprising a plurality of flexibly-connected piston-heads adapted to pass successively through the expansion-chamber in a common direction, coöperating revoluble winged gates located at the inlet end of the expansion-chamber and adapted 75 to be turned to allow the entrance of the piston-heads at intervals, by the successive contact of the piston-heads with the operative or alined wings of the gates, and cushion-springs carried by the piston-heads in advance of 80 their front sides, for contact with the wings, substantially as specified.

4. A fluid-pressure motor having an expansion-chamber, a piston comprising a plurality of spaced flexibly-connected piston-heads 85 adapted to pass successively through the expansion-chamber in a uniform direction, coöperating revoluble winged gates disposed at the inlet end of the expansion-chamber and adapted to be actuated by the successive engagement of the piston-heads with the operative or alined wings of the gates, and gate-locks for normally holding the gates in their 90 adjusted positions against rotary movement, and having trips for engagement by the piston-heads, whereby the gates are released preparatory to the entrance of a piston-head, 95 substantially as specified.

5. A fluid-pressure motor having an expansion-chamber, a piston comprising a plurality of spaced flexibly-connected piston-heads 100 adapted to pass successively through the expansion-chamber in a uniform direction, coöperating revoluble winged gates disposed at the inlet end of the expansion-chamber and 105 adapted to be turned to remove their operative or alined wings from the path of an entering piston-head, and advance and reverse gate-locks engaged with the gates to normally hold them in their adjusted positions, and 110 having means disposed in the path of the piston-heads, for engagement thereby, to release the gates, substantially as specified.

6. A fluid-pressure motor having an expansion-chamber, a piston comprising a plurality of spaced flexibly-connected piston-heads 115 adapted to pass successively through the expansion-chamber in a uniform direction, coöperating revoluble winged gates disposed at the inlet end of the expansion-chamber and 120 normally arranged with corresponding wings in alinement to form a fixed abutment, means for temporarily locking the gates in their adjusted positions and adapted to be disengaged 125 130

- at intervals to allow the entrance of the piston-heads, and yielding packing-strips carried by the gate-wings, the edge strips being provided with independently-movable members 5 or blocks, having independent actuating devices and having their faces constructed to correspond with the cross-sectional construction of the connection between the piston-heads, substantially as specified.
- 10 7. A fluid-pressure motor having an expansion-chamber, provided with an inlet-port, a piston comprising a plurality of spaced flexibly-connected piston-heads adapted to pass successively through the expansion-chamber
- 15 in a uniform direction, coöperating revoluble winged gates located at the inlet end of the expansion-chamber and having corresponding wings adapted to be arranged in alinement to form a fixed abutment contiguous to
- 20 the inlet-port, means for preventing reverse rotary movement of the gates during the expansion of the motive agent, an inlet-valve controlling said port, and operating connections between the inlet-valve and the piston,
- 25 the same including a rocker and a cam for actuating the rocker, substantially as specified.

8. A fluid-pressure motor having a casing, a plurality of parallel expansion-chambers located within the casing, a piston comprising a plurality of spaced piston-heads and an endless carrier connecting the same and extending at opposite sides through said expansion-chambers, guides for supporting the carrier, coöperating winged gates located at the 30 inlet end of each expansion-chamber and having corresponding wings adapted to be alined to form fixed abutments, means for temporarily locking the gates in their adjusted positions and adapted to be tripped at intervals to allow the entrance of the piston-heads successively into the expansion-chambers, and valve mechanism operatively connected with the piston for controlling inlet-ports of the expansion-chambers, substantially as specified.

In testimony that I claim the foregoing as my own I have hereto affixed my signature in the presence of two witnesses.

PETTER C. N. PEDERSON.
